UNITED STATES PATENT OFFICE.

WILLIAM H. HURT, OF FAYETTE, MISSOURI, AND JOHN E. CRAIG, OF CLEVELAND, TENNESSEE.

DESIGN FOR A KITCHEN-CABINET.

SPECIFICATION forming part of Design No. 32,184, dated January 30, 1900.

Application filed December 11, 1899. Serial No. 740,009. Term of patent 14 years.

To all whom it may concern:

Be it known that we, WILLIAM H. HURT, residing at Fayette, Howard county, Missouri, and JOHN E. CRAIG, residing at Cleveland, Bradley county, Tennessee, citizens of the United States, have invented and produced a new and original Design for a Kitchen-Cabinet; and we do hereby declare the following to be a full, clear, and exact description of the invention, such as will enable others skilled in the art to which it appertains to make and use the same.

Our invention relates to a design for a kitchen-cabinet; and it consists in the new and original design illustrated in the accompanying drawing.

The essential feature of the design is a rectangular cabinet having open top, closed back, and sides, a vertical open column of compartments at one side of the front of the cabinet extending from top to bottom thereof and of less than half the width thereof, a horizontal series of open compartments at the extreme bottom of the front of the cabinet, extending from the inner side of the said vertical column to the opposite side of the front of the cabinet, the rear walls of said horizontal series of compartments curving from the top and front thereof downwardly and backwardly and terminating short of the bottoms thereof, and a closed front surface of rectangular shape bounded on its top and one side edge by the top and side of the cabinet

and bounded at its bottom and remaining side edge by the horizontal series of compartments and the vertical column of compartments, respectively, the width of said closed rectangular surface being greater than half the width of the cabinet, and its height being greater than half the height thereof, as shown in the accompanying drawing, which is a perspective view of the cabinet, illustrating our invention.

In the accompanying drawing, 1 indicates one closed side of the cabinet. 2 indicates the plane rectangular closed surface upon the face thereof.

3 indicates the open top.

4 indicates the open vertical column of compartments at one side of the front of the cabinet.

5 indicates the horizontal open series of compartments at the bottom of the front of the cabinet, and 6 indicates the curved rear walls thereof.

55

What we claim is—

The design for a kitchen-cabinet substantially as herein shown and described.

In testimony whereof we affix our signatures in presence of two witnesses.

WILLIAM H. HURT.
JOHN E. CRAIG.
